ATTORNEY

UNITED STATES PATENT OFFICE.

CLEMENS J. GIESE, OF AMBIA, INDIANA.

ANTIREFILLABLE BOTTLE.

1,168,299.

Specification of Letters Patent. Patented Jan. 18, 1916.

Application filed September 14, 1915. Serial No. 50,670.

To all whom it may concern:

Be it known that I, CLEMENS J. GIESE, a citizen of the United States, residing at Ambia, in the county of Benton and State of Indiana, have invented certain new and useful Improvements in Antirefillable Bottles, of which the following is a specification.

An object of the present invention is to provide a new and improved anti-refillable bottle wherein the main closure valve is normally held in a superposed position through the medium of a loosely mounted rod and wherein the stopper carries means to normally retain the valve in engagement with the rod whereby when the stopper is removed and the bottle inverted the valve will become disengaged from the rod and the latter, by reason of its loose engagement, will fall into the bottle, at an angle, and thus permit the proper seating of the valve when the bottle is again brought to a normal position.

Another object of the invention is to provide an improved anti-refillable bottle that is extremely simple in construction and which, it is believed may be manufactured at a minimum cost.

Various other objects and advantages will become apparent during the continuance of the following description.

The above and other objects which will become apparent, are accomplished by such means as are shown in their preferred form in the accompanying drawings, described in the following specification and then more specifically pointed out in the appended claims.

In the accompanying drawings wherein like characters designate like parts throughout the several views; Figure 1 is a fragmentary view of an ordinary bottle showing my invention in its preferred embodiment in place therein. Fig. 2 is a similar view illustrating the supporting rod in displaced position and the valve in tight fitting engagement with its respective seat.

In the accompanying drawings the numeral 10 designates the body of an ordinary bottle whose bottom 11 is formed concave or convex as clearly shown. The neck 12 of the bottle is provided with a transverse baffle arm 13 and a slightly constricted valve seat 14. The valve 15 that is designed to fit the seat 14, is preferably formed of glass or other comparatively heavy material so that

its correct seating at the proper time will be fixed. The lower face of the valve is provided with a shallow recess 16 which may be vertically aligned with a similar recess 17 formed in the bottom of the bottle body. 60 A supporting rod 18 is provided, the ends of which are rounded so as to fit snugly within the respective orifices 16 and 17, the rod being of such length whereby when it is in an operative position the valve 15 will be 65 held out of engagement with its respective seat. This rod may be formed of any desirable material, yet it is pointed out that glass would prove very efficient. The stopper 19 that fits into the upper bore of the 70 bottle neck, to effectually close the passage of fluid therefrom, carries a pair of slightly diverging spring jaws 20, the latter being of such length as to swingingly engage the valve 15 and bent to hold the same in secure 75 engagement with the supporting rod 18. Now, when the stopper 19 is removed and the bottle uncovered, the valve 15 will seat upon the baffle arm 13 whereas the supporting rod 18 will also move in a similar direction. 80 When the valve 15 is seated upon the baffle arm the fluid from the body of the bottle will flow thereabout and continue to pass out through the remaining bore of the neck. However when the bottle is again 85 brought to a normal position the lower end of the rod 18 will engage the curved surface of the bottom of the bottle and tend to slope downwardly into a position shown in Fig. 2. Consequently its upper end will not in 90 any way impede the correct and positive seating of the valve 15 upon its respective seat. Moreover, when the rod 18 assumes this latter position it is evidence that the original contents of the bottle have been removed or tampered with in some manner. 95

From the foregoing it is believed that the advantages and novel features of my invention will be readily understood and therefore further detailed description is deemed 100 unnecessary.

In reducing my invention to practice I find that the form referred to herein as the most practical and preferred embodiment is the most efficient, but realizing that certain 105 conditions will necessarily vary in concurrence with the adoption of my device, I desire to emphasize the fact that various minor changes in the details of construction and in the proportion of parts may be resorted to 110

when required without sacrificing any of the advantages of my invention as defined in the appended claims.

Having thus fully described my invention, 5 what I claim as new and desire to secure by Letters Patent is:

1. In a device of the character described, a bottle having a neck portion, a valve mounted in said neck portion, a rod arranged in said bottle and adapted to support said valve, and means carried by the bottle stopper to normally retain the valve in engagement with the upper end of said rod.
2. In a device of the character described, 15 a bottle having a neck portion, a rod loosely mounted in said bottle and projecting into said neck portion, a valve in said neck portion normally supported by said rod out of engagement with its respective valve seat, a stopper adapted to be arranged in said neck, and means carried by said stopper to normally retain said valve in engagement with said rod.
3. In a device of the character described, 25 a bottle having a neck portion, the bottom of said bottle provided with a recess, a rod having its lower end seated in said recess, a valve in said neck, the under face of said valve provided with a recess for receiving 30 the upper end of said rod, said rod adapted

to normally retain said valve out of engagement with its respective valve seat, a stopper adapted to be arranged within said neck, and means carried by said stopper to normally retain said valve in engagement with 35 the upper end of said rod.

4. In a device of the character described, the combination with a bottle having a neck portion, and a bottom portion having its inner surface convexed, the bottom portion 40 of the bottle provided with a recess upon its inner face, of a valve loosely mounted in said neck and having a recess formed on its under face, a rod having its ends seated in said recesses to normally retain said valve 45 out of engagement with its respective valve seat, a baffle member arranged in said neck above said valve for limiting the movement thereof at certain times, a stopper adapted to be arranged in said neck, and means 50 carried by said stopper to normally retain said valve in engagement with the upper end of said rod.

In testimony whereof I affix my signature in presence of two witnesses.

CLEMENS J. GIESE.
